(57) **CLAIM**

The ornamental design for a cylinder support system, as shown and described.

DESCRIPTION

FIG. 1 is a perspective view of a cylinder support system showing our new design;

FIG. 2 is a left side view of the cylinder support system illustrated in FIG. 1 with the opposite side being a mirror-image thereof;

FIG. 3 is a front view of the cylinder support system illustrated in FIG. 1;

FIG. 4 is a right side view of the cylinder support system illustrated in FIG. 1;

FIG. 5 is a rear view of the cylinder support system illustrated in FIG. 1;

FIG. 6 is a top view of the cylinder support system illustrated in FIG. 1; and,

FIG. 7 is a bottom view of the cylinder support system illustrated in FIG. 1.

In the drawings, the broken lines depict unclaimed environmental subject matter only and form no part of the claimed design.

The cut away portions in the drawings indicate that the appearance of any portion of the article between the cut away lines forms no part of the claimed design.
